UNITED STATES PATENT OFFICE

ARCHIBALD MACKINNON, OF NEW YORK, N. Y.

TABLE

Application filed April 26, 1927. Serial No. 186,796.

This invention relates to improvements in folding or collapsible tables such as employed in banquet halls, mess halls and dining rooms for instances requiring the seating of a large number of persons.

One of the objects of my invention is to provide a folding or collapsible table having supporting legs constructed and arranged to be quickly set up to support the leaves of said table in one position and movable to a closed or inoperative position within a very restricted space so that the folded table may be conveniently transported or stored in a comparatively limited area.

Another object of my invention is to provide a folding or collapsible table of the character specified in which the supporting leg or legs is pivotally connected to a substantially narrow central table top so that when the said leg or legs are moved to their inoperative position, the combined width of the folded legs will be less than the width of the said top permitting the transportation and storage of the table in a very limited or restricted area.

A continued object of my invention is to provide a folding or collapsible table having a plurality of connected supporting legs movable transversely of a table top and hinged leaves therefor, said supporting legs being of a width considerably less than the width of the said top when moved to their closed and inoperative positions for convenient handling and storage in a comparatively limited space.

To enable others skilled in the art to more fully comprehend the underlying features of my invention and its possible modifications that the same may be understood and the practical applications thereof appreciated for the uses, purposes and objects intended, drawings depicting a preferred form are annexed hereto in which

Fig. 1 is a view showing my invention when assembled and set up for use.

Fig. 2 is a sectional view taken on the line 2—2 of Fig. 1.

Fig. 3 is a view partly in section showing the closed position of the supporting legs.

Fig. 4 is a bottom plan, 50
Fig. 5 is a sectional view showing the hinged leaf.

Fig. 6 is a view showing a slightly modified form of the invention.

Fig. 7 is a view taken on the line 7—7 of 55 Fig. 6.

Fig. 8 is a view showing the type of supporting leg illustrated by Fig. 7 when closed.

Fig. 9 is a detail showing the rod connection for the supporting legs. 60

Fig. 10 is a view of the actuating rod connecting the supporting legs.

Fig. 11 is a detail showing the connection of the central table top when employed in connection with stationary posts or pillars. 65

Referring now to the drawings wherein like reference characters designate corresponding parts throughout the several views, 5^a designates the table top which consists of a substantially narrow continuous board of 70 considerable length to which the side leaves 5, 6 are connected by strap hinges 7. The said leaves are preferably of the same length as the central top 5 but considerably wider and when opened lie in the same plane to provide a table top that may be employed for different purposes and uses. 75

The supporting means for the table comprise a plurality of substantially rectangular outside frames each having the vertical legs 80 8, 9 and top and bottom cross connecting bars 10, 11 fastened thereto, the said connecting bars being pivotally mounted for rotation on a rod 12 fastened to the top 5 and extending through the said top and bottom connecting bars and retained by a nut and washer. The width of the frames are substantially the width of the entire table top when the leaves are opened as clearly seen by Fig. 2 of the drawing. 90

Pivots mounted on each of the rods 12 and between the top and bottom bars 10, 11, I provide a second inside frame, substantially triangular in shape and comprising top and bottom cross bars 13, 14 and inclined legs 15, 16 attached thereto but on opposite sides thereof as shown more clearly by Fig. 1. The length of the legs 15, 16 are somewhat shorter than the legs 8, 9 in order that one frame may be swung on its pivot at right angles to the other in one position and within the frame in parallelism thereto in a second or inoperative position. In other words, when the frames are opened, four supporting legs are provided for the table, and when the frames are swung on the rods 12 to their inoperative positions, they are disposed in longitudinal alignment with the top 5 permitting the leaves to drop as shown in Fig. 3. In order that the outside frames may be swung to their operative positions at right angles to the table top, each of the strap hinges may be provided with a side flange 17 which acts as an abutment for the top cross bars 13.

From the above construction, it will be seen that I have provided a folding or collapsible table which may be of any desired length and in which the hinged leaves are properly supported by the rotatable frames which are capable of being rotated to an inoperative position to lie between said leaves and in longitudinal alignment with the top 5 for convenience in transportation and storage.

In order that the outer frames may be actuated or moved to their operative positions, I provide a connecting rod 18 attached to the corresponding legs of all the frames and which may be manipulated by hand to open the said frame transversely of the table top or at right angles thereto when the leaves are raised.

In Figs. 6 to 11 inclusive, a slightly modified form of the invention is shown, applicable for use under more specific conditions. In many instances, it is desired to position a foldable or collapsible table between pillars or posts 20, 21 at opposite ends or sides of a room. The table top 22 is therefore provided with semi-circular recesses 23 in the ends thereof to interfit the said pillars or posts to prevent relative, lateral movement. The leaves 24, 25 are also hingedly connected by means of strap hinges to the top 22 in the same manner as described in connection with the first form of the invention. The supporting means employed comprises a substantially triangular frame having a top cross bar 26 provided with a dowel or pin 27 extending into a recess through the center of the top 22. Connected to the top 22 are the rigid sides 28, 29 and at the apex of the frame a dowel or pin 30 is provided to fit within a recess 31 in the floor. The frame in this instance, therefore, is also capable of pivotal movement in an operative position at right angles to the

table top and hinged leaves to support the structure. The strap hinges employed also act as stops or abutments for the frames when opened. The actuating rod 18 is connected to the short links 18^a which are equipped with eyes 19^a to be fastened to the corresponding legs of the frames so that all of the frames may be opened simultaneously as described in connection with Figs. 1 to 4 inclusive. In both forms of the invention, it will be seen that the frames may be closed to lie entirely between the hinged leaves so that the width of the table in its inoperative position is comparatively narrow as compared to its open position.

While I have shown and described my invention with some degree of particularity, I realize that various changes and details of the structure may be altered and modified to meet specific conditions, uses and purposes. I therefore do not wish to be limited and restricted to the exact details as shown but reserve the right to make such changes and alterations as may fairly be included within the scope of the subject matter being claimed.

Having shown and described my invention what I claim as new and desire to secure by Letters Patent of the United States is:

1. A folding table of the class described comprising a narrow, longitudinally extending top, leaves hingedly connected to the top, a plurality of connected frames and vertical rods on which said frames may rotate, a separable second frame pivotally mounted on each of the rods for movement at right angles to the first mentioned frames, both of said frames being adapted for rotation as a unit to a closed, inoperative position in longitudinal alignment with the top and between the said leaves when closed and a rod constituting a pivot link connection between the supporting frames whereby the swinging of one supporting frame will produce a corresponding swing of the other support frames.

2. A folding table of the class described comprising a top, leaves and hinges connecting said leaves to the top, supporting frames pivotally connected to the top for movement at right angles thereto, said hinges constituting an abutment for said supporting means when opened, and interior supporting frames movable with the first mentioned frames as a unit in longitudinal alignment with the top and between the said leaves and a rod constituting a pivot link connection between the supporting frames whereby the swinging of one supporting frame will produce a corresponding swing of the other support frames.

3. A folding table of the class described comprising a top, leaves connected to the top, a plurality of rectangular supporting frames pivotally mounted for swinging movement at right angles to the top, a triangular frame rotatable within and at right

angles to each of the said rectangular supporting frames, both of said frames being movable as a unit to an inoperative position in longitudinal alignment with the top and between the said leaves and a rod constituting a pivot link connection between the supporting frames whereby the swinging of one supporting frame will produce a corresponding swing of the other support frames.

5 10 In testimony whereof I affix my signature.
ARCHIBALD MacKINNON.
